SEWING ACCESSORY CARRYING CASE

Cecile B. Edwards, Los Angeles, Calif.

Application June 17, 1957, Serial No. 46,614

Term of patent 14 years

(Cl. D87—5)

The decoration on the front panel is repeated on the rear.

I claim:

The ornamental design for a sewing accessory carrying case, as shown and described.
